UNITED STATES PATENT OFFICE.

GEORGE M. EAMES, OF BRIDGEPORT, AND JOHN C. RINGE, OF STRATFORD, CONNECTICUT, ASSIGNORS TO THE SINGER MANUFACTURING COMPANY, OF ELIZABETH, NEW JERSEY, A CORPORATION OF NEW JERSEY.

TAPE-THREADING MACHINE.

Application filed July 23, 1921. Serial No. 486,957.

To all whom it may concern:

Be it known that we, GEORGE M. EAMES and JOHN C. RINGE, citizens of the United States, residing, respectively, at Bridgeport and Stratford, in the county of Fairfield and State of Connecticut, have invented certain new and useful Improvements in Tape- Threading Machines, of which the following is a specification, reference being had 10 therein to the accompanying drawings.

This invention relates to improvements in machines for threading tape into articles, such as buttons and the like, and more particularly in the machine disclosed in our 15 pending United States patent application Serial No. 319,720, filed August 25, 1919.

The invention has for an object to avoid breakage of parts of the machine and possible injury to an operator upon the presentation to the threading implements of a button or like article in which the threading apertures are distorted, or otherwise not properly spaced or correctly positioned for entrance by said implements.

Another object of this invention is to provide means for automatically preventing the feeding of tape to the threading implements in the event that the article-apertures are not properly aligned with the threading implements for entrance by the latter.

The invention has for a further object to facilitate the straightening out of jams which may possibly occur in the article-hopper and the chute leading therefrom by articles clogging the passageways.

Other and minor objects of the invention will be apparent from the following description and claims.

In accomplishing the objects herein set forth, the present invention has been embodied, as improvements, in the machine clearly illustrated in our pending patent application before referred to. This machine comprises a plurality of reciprocating threading implements to which articles are automatically presented to be threaded with short lengths of tape. The tape is automatically drawn from a suitable supply, severed into desired lengths and presented to the 50 threading implements which seize the tape

and draw the free ends thereof through the article-apertures. The threaded articles are then automatically ejected from threading position.

To threading implements, in the prior machine referred to, are in the form of hook-needles which enter the apertures of an article to be threaded. If the apertures of the article are for any reason improperly positioned, it is apparent that breakage of the 55 article or of a machine part may occur. This not only occasions a loss by reason of wasted time and broken parts, but may injure an operator by flying pieces of the broken article or machine part. In order to entirely 60 overcome any possible defects of this character in the machine, the present invention comprehends the provision of a yielding connection between the threading implements and their actuating mechanism whereby if for any reason any obstruction is 65 offered to the free passage of the implements, movement of the latter is arrested without injury and without discontinuing the operation 70 of the actuating mechanism. When the 75 threading implements are yieldingly arrested in this manner, a device is permitted to become effective to open the tape-feeding jaws to release the tape.

According to the present improvement, 80 the article hopper is so arranged with respect to its driving connections as to permit of its ready removal from the machine to straighten out article-jams clogging the hopper or the chute leading therefrom.

In the accompanying drawings, Fig. 1 is a view in front side elevation and partly in section of a machine embodying the present improvements, omitting the button-hopper. Fig. 2 is a top plan view of the machine, omitting the overhanging arm and parts carried thereby but showing in section, the button-chute and the threading implements. Fig. 3 is a sectional view substantially on the line $x-x$ of Fig. 2. Fig. 4 is a sectional view substantially on the line $y-y$ of Fig. 2. Fig. 5 is a front end elevation of the button-hopper and its actuating gearing. Fig. 6 is a sectional view substantially on the line $z-z$ of Fig. 1. Fig. 7 is an enlarged detail 95 100

view of the threading-implement carrying bar. Fig. 8 is a plan view of the ball-retainer ring sustaining the article-hopper.

Referring to the drawings, the present improvements are embodied in a machine supported on a base 1 and comprising a bed-plate 2 from which rises the hollow standard 3 of the tubular overhanging bracket-arm 4 terminating in the head 5.

10 Journaled in suitable bearings provided in the bracket-arm 4 is a rotary actuating shaft 6 carrying at one end a belt-pulley 7 and at its opposite end a crank 8 connected by means of a link 9 with a tubular needle-15 actuating bar 10. The needle-actuating bar 10 is journaled for endwise reciprocation in bushings, as 11, provided in the head 5 of the machine frame. Arranged telescopically within the tubular bar 10 is a needle-bar 12 20 to the lower end of which is secured, by means of a screw 13, a collar 14 having a laterally projecting arm 15. Secured in suitable apertures provided in the collar 14 are the shanks of two threading implements, 25 as 16, in the form of hook-needles. Intermediate its ends there is secured to the needle-bar 12, by means of screws as 17 a guide-block 18 fitted into a slideway afforded by the walls of an elongated slot 19 provided 30 in a tubular actuating bar 10. Threaded into the upper end of the tubular bar 10 is an adjusting screw 20, between which and the upper end of the needle-bar 12 is interposed a coiled spring 21. The spring 21 is 35 compressed sufficiently by the adjustable screw 20 to normally maintain the slide-block 18 in engagement with the lower end of the slot 19 whereby the needle-bar 12 will follow the reciprocating movements of the bar 10. If, however, any unusual element, 40 such as an improperly positioned button or one in which the apertures are spaced differently from the spacing of the threading implements, is interposed in the path of 45 movement of said implements, the spring 21 will yield to permit continued movement of the actuating mechanism without causing breakage of any of the parts.

As in the machine of our prior application 50 hereinbefore referred to, the articles to be threaded with short sections of tape are automatically presented into threading position, but the present machine includes improved means for supporting and actuating the article-hopper and chute. Referring more particularly to Fig. 5 of the accompanying drawings, a bracket 22 is suitably secured upon the rear side of the head 5 and is provided with spaced bearing lugs, as 23. Rigidly secured in suitable apertures provided in the lugs 23 is a stationary section 24 of a button-chute formed with a longitudinal slot 25 for view of the articles passing therethrough. The section 24 of the 55 button-chute extends upwardly beyond the

upper lug 23 and loosely surrounding this extension is a washer 26 resting upon the upper lug 23. Resting upon the washer 26 are a plurality of spaced bearing balls, as 27, held in a ball-retainer 28, while a washer 29 similar to the washer 26 is superposed upon the balls and is free to rotate around the chute-section 24.

A spur-gear 30 rests upon the washer 29 and is suitably secured upon the lower end of an article-hopper 31 within which is disposed a bushing 32 having a beveled upper end to coincide with the inner surface of the hopper. The bushing 32 is shouldered on its inner surface adjacent the beveled portion which shoulder abuts against the upper end of the chute-section 24, thereby affording a smooth passageway for the articles. Suitably secured within the hopper 31 is an article sieve 33 having a central aperture 34 eccentrically entered by a stationary article-agitator 35 adjustably carried by a supporting arm 36 secured by means of a thumbscrew 37 within a socket provided in the bracket 22.

In order to rotate the hopper 31, the spur-gear 30 meshes with a similar gear 38 secured upon the upper end of a shaft 39 journaled in suitable bearings provided in the lugs 23. At its lower end the shaft 39 carries another spur-gear 40 in driving engagement with a spur-gear 41 rigidly secured upon the upper end of a rotary section 42 of the chute; the section 42 being in vertical alinement with the stationary chute-section 24 and journaled in suitable bearings provided in the head 5. Also secured upon the chute-section 42 and below the spur-gear 41 is a belt-pulley 43 actuated by a belt 44, running over idlers, as 45 and embracing a belt-groove 46 provided in the driving pulley 7. From the foregoing it will be observed that rotation of the belt-pulley 7 rotates the chute-section 42 and the hopper 31, leaving the chute-section 24 stationary. Further, by means of the described construction, the hopper 31, together with its attached spur-gear 30 when desired may be readily lifted off the stationary chute-section 24 and in fact the bracket 22, together with all the parts carried thereby, may be detached from the machine, both without disturbing the driving relationship of the belt 44. This readily permits straightening out of any article-jams which may possibly occur, while the slot in the stationary chute-section 24 provides for access to the articles particularly during the operation of the machine. The gearing for driving the article-hopper is preferably enclosed by a two section housing 47. These housing sections rest upon the bracket 22 and are secured together by means of screws as 48.

In order to automatically transfer the ar-

ticles from the lower end of the rotary chute-section 42 into threading position, there is employed substantially the same mechanism as was embodied in the machine 5 of our prior patent application hereinbefore referred to and as this mechanism, per se, does not form part of the present invention, only a general description thereof need now be repeated.

10 The chute-section 42, at its lower end which is immediately above the bed-plate, is formed with a longitudinal slot entered by a light spring 49 adapted to engage the lowermost of the articles of the column 15 thereof supported by the chute. The spring 49 serves to cause the article engaged thereby to rotate with the chute-section 42 in order to properly position the article upon registering pins to be later described.

20 Supported for horizontal sliding movements in suitable ways provided for the purpose on the bed-plate 2 is a slide-block 50 having depending ears 51 connected by means of a link 52 with the upper end of a
25 rock-arm 53. The rock-arm 53 projects upwardly from a sleeve 54 loosely journaled between two collars as 55 upon a rock-shaft 56 supported by frame-lugs, as 57. A coil-spring 58 connects the rock-arm 53 with the
30 machine frame and acts to hold a roller 59 carried by the rock-arm against a cam 60. The cam 60 is secured upon a rotary shaft 61 suitably journaled in the machine frame and actuated by means of quartering cranks

35 and pitmen 62 from the main-shaft 6. Adjustably secured upon the rearward end of the slide-block 50 by screws, as 63, so as to extend forwardly in spaced relation with respect to the upper surface of the slide-block 40 is a longitudinally slotted feed-slide

40 block is a longitudinally sloping feed plate 64 whose forward or article-engaging edge is shaped to correspond substantially with the contour of the articles to be threaded. Interposed between the feed-

45 slide plate 64 and the upper surface of the slide-block 50 is a stationary longitudinally-slotted article-supporting plate 65 adjustably secured upon the bed-plate by screws, as 66.

As may be observed in Figs. 2 and 3 of the drawings, the plate 65 extends forwardly to a point closely adjacent the vertical plane of the path of movement of the two threading implements to in part support the articles during the threading thereof. A

55 complementary article-supporting plate 67 extends from the opposite side toward the threading implements and overlies a spacing block 68 secured upon the bed-plate 2 by screws, as 70, which also secure an article 60 stripper-plate 71 provided with a transverse slot 72 to afford clearance for the threading implements.

It will be apparent that the function of the feed-slide plate 64 is to push into 65 threading position the articles dropping

from the chute upon the supporting plate 65. It is, however, essential that the apertures of the articles be properly positioned for entrance by the threading implements. To this end there is provided a slide-bar 73, disposed within a clearance groove 74 in the slide-block 50 and beneath the supporting plate 65. The slide-bar 73 carries at its forward end two article-registering pins 75 projecting upwardly through the slotted article-supporting plate 65 and feed-slide plate 64. The rearward end of the slide-bar 73 in retracted position rests upon the cross-bar of a substantially U-shaped support 76 adjustably secured by screws, as 77, upon the bed-plate 2. Intermediate its ends the slide-bar 73 is provided with a hook 78 connected by means of a coil-spring 79 with an upwardly extending arm 80 on the support 76. The spring 79 serves to hold the slide-bar 73 against the under surface of the supporting plate 65 and tends to hold the slide in retracted position.

In the retracted position of the slide-bar 73, the pins 75 are directly beneath the delivery end of the chute-section 42, the lowest article in the chute, when not registered, resting upon said pins. Rotation of the article with the chute by reason of the action of the spring 49 brings the apertures of the former into alinement with the pins 75 whereupon the article drops by gravity upon the article-supporting plate 65. The cam 60 now acts to advance the feed-slide plate 64 which engages the pinned or registered article and advances it into threading position, as illustrated in Fig. 3 of the drawings. The threading implements 16 now descend to enter the apertures of the article and thereby depress the pins 75, which action is permitted by the clearance provided by the groove 74. The pins, when clear of the article are immediately retracted by the spring 79 into their initial position, while the feed-slide 64 is returned during the upward movement of the implements 16.

A tape T is led from a suitable supply through an aperture provided in an ear 81 projecting laterally from a guide-flange 82 of a tension-supporting plate 83, supported for swing-out movement upon a stud-screw 84 and held in operative position by a registering pin 85 and a coil-spring 86. The tape T passes from the ear 81 past a tensioning device 87 into a tape-guide 88 pivoted near its rearward end upon a pin 89 carried by a block 90 secured upon the machine bed-plate. A guide 91 maintains the tape-guide 88 in a vertical plane during its pivotal movements. The block 90 is provided with a transverse slot entered by a tape-guide tilting bar 92 of which the advance end is formed as an inclined fork 93 straddling the tape-guide 88, whereby longi- 115 120 125 130

tudinal movements of the bar 92 cause positive swinging movements of the tape-guide 88 upon its pivot.

The bar 92 is adapted to be guided in its reciprocating movements by a slot provided in a block 94 suitably secured upon the bed-plate. A coiled spring 95 connected at its opposite ends to the block 94 and the bar 92 tends to hold the latter in retracted position, with the delivery end of the tape-guide depressed whereby the end of the tape is held in the path of movement of tape-feeding means to be hereinafter described. The bar 92 is forcibly advanced to raise the tape-guide by one end 96 of a two-armed lever, fulcrumed intermediate its ends upon the support 76 and of which the other end 97 extends into the path of movement of the slide-bar 73. The advancing movement of the bar 92 is limited by the engagement of the adjustable plate 98 secured thereupon with the block 94. From this construction it is apparent that the position of the delivery end of the tape-guide is dependent upon the movement of the slide-bar 73 carrying the article registering pins, inasmuch as the spring 79 is relatively stronger than the spring 95. In other words, if no article is dropped into register with the pins, then the feed-slide 64 advances idly, the registering pins 75 remaining stationary, which is permitted by the slotted feed-slide. When this occurs, the slide-bar 73 remains in engagement with the end 97 of the two-armed lever under the action of the spring 79, thereby holding the bar 92 in its advance position. Therefore if no article is advanced into threading position, the delivery end of the tape-guide 88 remains elevated; on the contrary, every time an article is transferred from the chute to threading position, the tape-guide is depressed by reason of the movement of the slide-bar 73 and the action of the spring 95 upon the bar 92.

Referring now more particularly to the tape-feeding means, a suitable slideway is provided on the bed-plate 2 for a reciprocating plate 99 transmitting actuation to the tape-feeding jaws, article-ejector and the tape-positioning fingers. Upon the advance end of the plate 99 is fulcrumed by means of a screw 100, a two-armed lever of which one arm 101 is connected by means of a longitudinally adjustable two-part link 102 with a crank-disk 103. This connection preferably includes a slide-block 104 adjustably secured in any usual manner in a radial way 105 and pivotally connected by means of a screw 106 with the link 102. The crank-disk 103 is carried by the upper end of a rotary shaft 107 journaled in a bearing boss 108 of a bracket 109 suitably secured upon the bed-plate 2. At its lower end the shaft 107 carries a bevel-gear 110, which is actuated from a similar gear 111 carried by

the shaft 61. The free end of the other arm 112 of the two-armed lever forms one member of tape-gripping jaws of which the cooperating member is formed by an ear 113 upturned from the plate 99. Secured by means of a screw 114 and a steady-pin 115 upon the plate 99 is a cam-member 116 having an upwardly projecting pin 117 limiting movement of the arm 112 in one direction. It will be understood that when the plate 99 is in its extreme retracted position, i. e., toward the right in Fig. 2 of the drawings, and before it commences its advancing movement toward the left, the first action caused by the movement of the link 102 is to swing the two-armed lever until the arm 112 thereof engages the pin 117 thereby opening the tape-gripping jaws. Further oscillation of the arm 112 being prevented by the pin 117, the plate 99 is bodily advanced until the open jaws are immediately in advance of the delivery end of the tape-guide 88. The link 102 now reverses its movement, first causing the arm 112 to swing on its pivot thereby closing the jaws to grip the tape therebetween. The continued movement of the link 102 then causes the plate 99 to be retracted, consequently drawing the tape across the path of the threading implements. The path of movement of the tape-gripping jaws is such that only when the delivery end of the tape-guide 88 is in its lowered position will the jaws seize the tape, for the purpose previously described.

Should it occur that the apertures in the article to be threaded are not properly aligned for entrance by the threading implements, whereupon the latter do not complete their descending movement as described herein, then it is undesirable that the tape be fed owing to the waste of tape and the possibility of clogging the operating parts of the machine. To this end means is provided that is operative under this abnormal condition to cause the jaws to release the tape as the tape-feeding movement is begun. An arm 118 is pivotally secured by means of a screw 119 upon a bracket 120 suitably secured upon or formed integral with the bed-plate. The free end of the arm 118 is forked to form spaced members 121 and 122 permitting passage therebetween of an article ejector later referred to. A spring 123 tends to yieldingly hold the arm 118 in raised position against a stop-lug 124 upon the bracket 120. The upper arm 121 lies in the path of movement of the arm 15 projecting laterally from the needle-clamp collar whereby, during the normal operation of the machine, the arm 118 is depressed against the action of its lifting spring 123 at each reciprocation of the needle-bar. If, however, the threading implements are arrested in their descending movement by contact with an article

or for any other reason, then the lower member 122 by remaining in its raised position lies during the tape-feeding movement in the path of a lug 125 provided on the arm 112 of the tape-gripping jaws. The engagement of the lug 125 with the member 122 causes said arm 112 to rock sufficiently to open the jaws and release the tape.

Fulcrumed upon the bed-plate 2 by means 10 of a screw 126 is a tape-positioning arm 127 having at its free ends spaced and upwardly projecting tape-positioning fingers, as 128 and carrying intermediate its ends an adjustable cam-plate 129. The cam-plate 129 15 is adapted to be engaged by a cam-lug 130 provided on the cam-member 116 so that during the advancing movements of the plate 99, the fingers 128 are diverted against the action of a spring 131 out of the path 20 of movement of the tape-gripping jaws. After the plate 99 has been retracted sufficiently to permit the cam-lug 130 to ride the rounded end of the cam-plate 129, the spring 131 acts to cause the fingers 128 to engage the 25 tape upon opposite sides of the ascending threading implements and hold it against the shanks of the latter to insure seizure of the tape by the hooks of the implements. It will be observed that a clearance slot 132, 30 shown in dotted lines in Fig. 2 of the drawings, is provided in the article-supporting plate 67 to permit the movement of one of the fingers 128.

Suitably secured upon the shaft 56 is a 35 knife-carrying arm 133 carrying a cam-engaging element 134 acted upon by a cam 135 provided upon the rotary shaft 61. A coiled spring 136 surrounding the shaft 61 and one end of which engages the machine 40 frame and the other end a collar 137 carried by the shaft, holds the cam-element 134 in contact with its actuating cam. Adjustably secured upon the knife-carrying arm 133 is a knife-blade 138 of which the 45 severing edge is movable across the path of the tape and coacts with a stationary blade 139 suitably secured upon the block 90. By means of this construction the 50 desired lengths of tape are automatically severed during the operation of the machine.

A tape-holding finger 140 is suitably secured upon a vibratory arm 141 projecting laterally from an oscillating shaft 143 suitably journaled in the machine frame. Secured upon the shaft 143 is an arm 144 carrying a roll 145 in engagement with a cam 146 upon the rotary shaft 61. The roll 145 is held in engagement with its 55 actuating cam by means of a coil-spring 147 surrounding the shaft 143 and one end of which enters an aperture in a collar 148 adjustably secured upon the latter shaft while the other end bears against a portion 60 of the machine frame. The function of

the finger 140 is to engage the tape between the apertures of the article and hold the tape against bodily movement during the threading operation, thereby insuring that the free ends of the threaded tape are of 70 substantially equal lengths.

As in our prior patent application hereinbefore referred to, there is provided an article-ejector 149, a guard 150 and a chute 75 151 but, as these parts form no direct part of the present invention, no further description thereof is deemed necessary.

Having thus set forth the nature of the invention, what we claim herein is—

1. In a machine for threading short sections of tape into buttons, in combination, a threading-implement carrying bar, a plurality of hooked threading-implements carried by said bar, a button-holder adapted to sustain a button in position for entrance by said threading-implements, a reciprocating bar, means for reciprocating said bar, and a yielding connection between said bars normally causing movement of said bars in unison but permitting abnormal arrest of the 90 implement-carrying bar during the continued movement of the reciprocating bar upon the occasion of an implement striking a button sustained by said button-holder. 95

2. The combination in a machine having a rotary actuating shaft and a threading-implement, of a tubular bar, operative connections between the actuating shaft and said tubular bar for reciprocating the latter, a threading-implement carrying bar arranged telescopically within the tubular bar, a coacting guide-block and guideway provided on said bars preventing relative axial movement thereof, and a yielding connection between said bars normally causing movement thereof in unison but permitting abnormal arrest of the implement-carrying bar during the continued movement of the tubular bar. 100 105

3. The combination in a machine having a rotary actuating shaft and a threading-implement, of a tubular bar, a slotted guideway provided in said tubular bar, operative connections between the actuating shaft and said tubular bar for reciprocating the latter, a threading-implement carrying bar arranged telescopically within the tubular bar, a guide-block carried by said threading-implement carrying bar and entering the guideway in the tubular bar, and a spring seated within said tubular bar acting to maintain said guide-block in a definite position in said guideway to cause reciprocation of said bars in unison but permitting arrest of the movement of the threading-implement carrying bar during the continued movement of the tubular bar. 110 115 120

4. In a machine for threading short sections of tape into buttons and like apertured articles, the combination with a rotary ac- 125 130

tuating shaft and a threading-implement, of operative connections between the actuating shaft and said threading-implement permitting the movement of the latter to be abnormally arrested during the continued rotation of the actuating shaft, tape-feeding means, and means for causing said tape-feeding means to release the tape on the occasion of an abnormal arrest of the movement of the threading-implement.

5. In a machine for threading short sections of tape into buttons and like apertured articles, the combination with a reciprocating threading-implement, means for automatically presenting articles into threading position, tape-feeding means comprising tape-gripping jaws, and means for opening said jaws to release the tape when an aperture of the article to be threaded is not aligned with the threading-implement.

15. In a machine for threading short sections of tape into buttons and like apertured articles, the combination with a reciprocating threading-implement, means for reciprocating the same, of tape-feeding means effective to present the tape to said threading-implement, and means for rendering said tape-feeding means ineffective in the event that an aperture in the article to be 20 threaded is improperly alined for entrance by said threading implement.

25. In a machine for threading short sections of tape into buttons and like apertured articles, the combination with a rotary actuating shaft and a threading-implement carrying bar, of operative connections between the actuating shaft and said threading-implement carrying bar for reciprocating the latter and permitting abnormal arrest of the movement of said bar during the continued rotation of the actuating shaft, tape-feeding means comprising tape-gripping jaws and means for actuating the same, a cam element normally positioned in the path of movement of said jaws adapted to open the jaws to release the tape, and means for displacing said cam element during the normal reciprocation of the threading-implement carrying bar.

30. In a machine for threading short sections of tape into buttons and like apertured articles, the combination with a rotary actuating shaft, and a threading-implement carrying bar, of means for reciprocating said bar from the actuating shaft including a yielding connection permitting arrest of the article penetrating movement of the bar during the continued movement of the actuating shaft, tape-feeding means including tape-gripping jaws and means for actuating the same, a vibratory arm, means tending to yieldingly maintain said arm in a determined position, a cam-surface carried by said arm adapted to engage the tape-feeding jaws to open the same, and means for deter-

mining the effectiveness of said cam-element by the movement of the threading-implement carrying bar.

9. In a machine for threading short sections of tape into buttons and like apertured articles, the combination with a reciprocating threading-implement and means for reciprocating the same, of tape-feeding means comprising tape-gripping jaws, and means for actuating said jaws including a rotary crank-disk and a link connecting said crank-disk with said jaws, and means permitting radial adjustment of the link connection with said crank-disk.

10. In a machine for threading short sections of tape into buttons and like apertured articles, the combination with a rotary shaft, a threading-implement, and means for reciprocating the threading-implement from the rotary shaft, of means for automatically presenting articles to be threaded to said threading-implement including a rotary article hopper, a stationary chute section leading from said hopper, a rotary chute section in alinement with the stationary chute section, means for rotating the rotary chute section and the hopper, and means for automatically transferring the articles from the rotary chute section to threading position.

11. In a machine for threading short sections of tape into buttons and like apertured articles, the combination with a rotary actuating shaft, a threading-implement and operative connections between the rotary shaft and the threading-implement for reciprocating the latter, of means for automatically presenting articles to be threaded to said threading-implement including a rotary article hopper, a stationary chute section leading from said hopper, a rotary chute section in alinement with the stationary chute section, means for rotating the rotary chute section and the hopper, and supporting means for said hopper permitting its detachment from the stationary chute section without disturbing the driving connections for the rotary chute section.

12. In a machine for threading short sections of tape into buttons and like apertured articles, the combination with a rotary actuating shaft, a threading-implement and operative connections between the rotary shaft and the threading-implement for reciprocating the latter, of means for automatically presenting articles to be threaded to said threading-implement including a rotary article hopper, a stationary chute section leading from said hopper, a rotary chute section in alinement with said stationary chute section, means for rotating the rotary chute section, and driving gearing between the rotary chute section and the hopper for rotating the latter.

13. In a machine for threading short sections of tape into buttons and like apertured

articles, the combination with a rotary actuating shaft, a threading-implement and operative connections between the rotary shaft and the threading-implement for reciprocating the latter, of means for automatically presenting articles to be threaded to said threading-implement, including a rotary article hopper, a stationary chute section leading from said hopper, a rotary chute section in alinement with said stationary chute section, means for rotating the ro-

tary chute section, driving gearing between the rotary chute section and the hopper for rotating the latter, and a bracket detachably secured upon the machine for sustaining the rotary hopper, its driving gearing and the stationary chute section. 15

In testimony whereof, we have signed our names to this specification.

GEORGE M. EAMES.
JOHN C. RINGE.
